EXTRACTIVE FRACTIONATION PROCESS

Lloyd C. Fetterly, Long Beach, Calif., assignor to
 Shell Development Company, San Francisco,
 Calif., a corporation of Delaware

Application April 15, 1947, Serial No. 741,676

7 Claims. (Cl. 260—666)

1

This invention relates to a process for the extractive fractionation of organic compounds. More particularly, it relates to improvements in the process of fractionally effecting organic compounds from mixtures thereof by the use of such complex-forming agents as urea and thiourea.

The fractionation of mixtures of organic compounds presents complex problems, both technical and economic. For example, the separation of mixtures of closely allied isomers, such as octane from iso-octane, is difficult by any of the more reasonably economic procedures, such as fractional distillation. Further, efficiency of conversion procedures such as alkylation, isomerization and cyclization is reduced if feed stocks are not of the correct composition, either during the primary feed state or in recycling operations.

In most of such conversion reactions an equilibrium mixture is generally obtained comprising fixed ratios of unconverted feed stock and the desired product. If the feed stock initially contains some of the conversion product, such as from a previous cycle through the converter, the amount of conversion is correspondingly reduced.

The two principal means for fractionation of such mixtures on a commercial scale have been by fractional distillation and by solvent extraction. Recently, however, a new method has been shown to be suitable for large scale separations, namely extractive crystallization with urea. It was found that urea forms crystalline complexes with organic compounds of substantially straight chain structure, while it appears to be inert in this respect toward branched compounds such as the isoparaffins, or cyclic compounds such as most aromatics and naphthenes. The complexes so formed are of indeterminate structure, but appear to be unstable molecular complexes rather than true chemical reaction products. This is indicated by their unstable character and the consequent ease of the regeneration of their components, namely urea and the unaltered organic compound.

When thiourea is the complex-forming agent employed the complexes formed thereby are usually of a substantially different character in that thiourea forms complexes with organic compounds having either a branched configuration or a cycloaliphatic structure. Under normal operating conditions thiourea forms only minor amounts of complexes with organic compounds of straight chain structure, such as the normal paraffins.

Mixtures of these complex-forming agents have been employed to extract normal and branched

2

non-aromatic compounds as well as naphthenes from mixtures containing other types of compounds usually in excess. This latter process is usually employed for the purification of aromatics such as benzene, toluene, etc.

These processes are particularly applicable to the refinement of petroleum or other hydrocarbon mixtures, especially those of unbranched structure (which may be suitably fractionated by complex formation with urea) or hydrocarbons of branched chain or saturated cyclic structure (which readily form complexes with thiourea). The general procedure known to the prior art comprised treatment of such mixtures with a solution of the complex-forming agent. Under these circumstances a mixture of complexes usually was formed. This was due to the characteristics of the complex-forming agents whereby under a given set of operating conditions certain classes of compounds formed complexes with the agents present. Thus, if both isoparaffins and naphthenes were present in a mixture of hydrocarbons, the treatment of such a mixture with thiourea resulted in the formation of complexes of both of these types of hydrocarbons with thiourea. For many purposes the presence of one or another type of compound in admixture with other types is undesirable. If, for example, this process were being used for the preparation of high octane gasoline, the presence of naphthenes in the product would be undesirable. Therefore, an improvement upon the known process would comprise a revision thereof whereby the final product substantially excluded naphthenes and largely comprised isoparaffins.

In a number of instances a mixture of organic compounds contains a relatively minor fraction of material which will form crystalline complexes with one of the above agents. It has been noted that if only a minor amount of complexes are formed and thereafter separated from the mixture by filtration the thin layer of crystals tends to form a dense layer which clogs the filter cloth and thus reduces the efficiency of the filtration step.

It is an object of this invention to improve extractive fractionation processes, particularly those wherein the complex-forming agent is either urea or thiourea. It is another object of this invention to provide for the production of more highly fractionated materials than those heretofore possible by the subject extractive fractionation processes. It is a further object of this invention to improve the efficiency of the separation step, avoiding the clogging of filters. Other

objects will become apparent during the following discussion.

Now, in accordance with this invention, it has been found that the fractionation of mixtures of organic compounds by the subject extractive fractionation processes may be improved by recycling part of the complexes back to the mixture prior to the separation step. By "part of the complexes" is meant a portion of the organic compounds extractively fractionated from the original mixtures, either in the form of the unaltered complex or in its regenerated form free of any complex-forming agent. Still in accordance with this invention, it has been found that the efficiency of separating complexes from their mixtures with other compounds may be raised by the step described above. Again in accordance with the present invention, it has been found that the feed may be enriched in a desired fraction by employing the above step as more fully described hereinafter.

In carrying out the process of the present invention, mixtures of organic compounds are contacted with a complex-forming agent (suitably either urea or thiourea), and passed to a separator wherein the complexes are separated from the raffinate. By "raffinate" is meant that portion of the original mixture which fails to form complexes with the agent present under the conditions employed. Following isolation of the complexes, the process according to the present invention comprises two alternative steps: the complexes may be passed to a regenerator or part of the complexes may be recycled to the mixer and the remainder sent to the regenerator. By "mixer" is meant that apparatus wherein the mixture of organic compounds is contacted with a complex-forming agent. If the latter alternative is employed the fraction to be returned to the mixer is predetermined by the conditions which it is desired to maintain in the mixture as well as by the desired composition of the final product. The complexes may be fractionated into any type of desired fractions, either according to molecular weight, chemical type, structural type, solubility, etc. The fractionation may be conducted by fractional crystallization from a lean solvent wherein only one part of the complexes will dissolve while the remainder are unaffected. Alternatively, the complexes may be fractionated by melting point, the temperature being raised until a particular fraction of the complexes are liquid and the remainder are unaffected at which point one phase or the other is recycled to the mixer. Other types of fractionating the complexes will be more or less obvious to those familiar with the art of fractionation.

The fraction of the complexes returned to the mixer enrich the feed in regard to that particular type of organic compound returned in complex form. Thus, the total amount of complexes separated thereafter from the enriched feed will be altered to the extent of this addition. This recycling of a fraction of the complexes may be conducted to the point at which the complexes finally separated have a desired composition. From the standpoint of efficiency this should be effected in a minimum number of recycling operations. By the addition of complexes to the mixer a heavier cake of crystals can be built up on the filter (if such is the separating means). It has been found that a relatively thick cake of such crystals is structurally more porous than a thin densely formed layer such as is obtained when the original mixture contains only a small amount of complex-forming organic compounds.

At times it is undesirable to fractionate the complexes as described above. For example, some of said complexes are relatively unstable and tend to decompose if heated to any appreciable extent, or have substantially the same solubility throughout, thus prohibiting fractional crystallization. Under such circumstances the total amount of complexes may be passed directly from the separator to a regenerator wherein the complex-forming agent and the organic compounds in complex form therewith are separated in such a way as to recover the agent in its original form and separately recover the organic compounds extended therewith. The conditions of regeneration allow a second step at which fractionation may be conducted whereby part of the product is recycled to the feed and part is sent to its final destination. For example, one means of regenerating organic compounds from their complexes comprises simple distillation, whereby the complex decomposes and at least part of the organic compounds are distilled leaving residual compounds and complex-forming agents behind. It will be readily appreciated that the conditions of distillation may be adjusted to the point that a fraction of a desired boiling range may be recovered either as a distillate or as a bottoms from a distillation step. Other means of regeneration are more fully described hereinafter at which point other types of fractionation of the products recovered will be described.

The fraction of the regenerated compounds recycled to the feed enriches the latter in that particular type of compound. Since the material returned to the feed is of a type which will form a complex with the agents employed, a sufficient amount of such agents must be possible to form complexes not only with the active material already in the feed but also with the recycled compounds. It is undesirable to recycle at this stage if the fractionation as described hereinabove can be effectively conducted. This is due to the fact that it is necessary to form and regenerate complexes more than once thus, decreasing the efficiency of the operation. However, if the regenerated compounds can be fractionated in a particular way to arrive at a desired fraction more effectively than when in complex form, then such multiple complex formation and regeneration becomes necessary.

By way of illustration, reference may be made to the drawing which comprises a flow diagram for the fractional extraction of mixtures of organic compounds in accordance with the method of the present invention. For this illustration a mixture of petroleum hydrocarbons comprises isoparaffins, normal paraffins, and naphthenes which would be contacted with thiourea. The mixture of hydrocarbons and a saturated alcoholic solution of thiourea are introduced to a mixer 1 at room temperature. The mixture is stirred for a short length of time to permit maximum contact of the thiourea solution with the hydrocarbons. Crystalline complexes form between thiourea and the hydrocarbons of naphthenic and isoparaffinic structure. The total mixture is sent to a separator 2, wherein the raffinate is filtered away from the crystalline complexes. A final product is desired which is to be a mixture of naphthenes and isoparaffins having a minimum boiling point of about 100° C. The mixture of complexes separated as described above is too unstable to fractionate by distillation. Therefore, it is sent directly from the separator 2 to the regenerator 4 wherein the com-

plexes are heated to their decomposition temperature and are fractionally distilled, the temperature of distillation being adjusted to the point whereat the hydrocarbons which distill have boiling points below the minimum desired final product. The bottoms from this distillation comprise isoparaffin and naphthenic hydrocarbons having a minimum boiling point of the desired range in admixture with regenerated thiourea. The latter separates from the hydrocarbons and may be recycled for further complex formation. In order to enrich the original feed stock in the desired isoparaffin and naphthene fraction, part of the latter regenerated hydrocarbons are recycled to the mixer 1 while the remainder is passed to storage. By recycling this fraction to the mixer the feed is enriched in the type of hydrocarbon having the predetermined boiling range thereafter the complex formation and separation are conducted as described above. The separation step constituted the formation of a relatively heavy filter cake of crystalline complexes which was highly porous and allowed faster filtration than was possible during the initial separation described above.

The mixtures of organic compounds which may be treated with urea by the process of the present invention comprise compounds having substantially normal structure and/or compounds having a predominating substituent of substantially normal structure. Conditions may be employed whereby certain normal organic compounds are separated from other normal organic compounds, or from the other organic compounds such as isoparaffins, aromatics, naphthenes, etc. The organic compounds of normal structure which may be formed into complexes by the process of the present invention include both saturated and unsaturated compounds, especially the paraffins, and olefins. The normal compounds may be of a number of types, such as hydrocarbons, alcohols, ketones, aldehydes, esters, amines, amides, sulfides, disulfides, mercaptans, acids, halogenated compounds, ethers, nitro-compounds, silicones, carbohydrates, etc. The hydrocarbons respond especially well to the process of the present invention.

Suitable hydrocarbons which form crystalline complexes with urea include the paraffinic hydrocarbons such as butane, pentane, hexane, heptane, octane, nonane, decane, undecane, dodecane, tridecane, tetradecane, pentadecane, hexadecane, heptadecane, octadecane, nonadecane, eicosane, etc.

Olefin hydrocarbons which may be treated by the process of the present invention include 1-butene, 2-butene, 1-pentene, 2-pentene, 1-hexene, 2-hexene, 3-hexene, 1-heptene, 2-heptene, 3-heptene, 1-octene, 2-octene, 3-octene, 4-octene, 2-nonene, 3-nonene, 4-nonene, 1-decene, 2-decene, 3-decene, 5-decene, 1-undecene, 2-undecene, 5-undecene, 1-dodecene, 6-dodecene, 1-tridecene, 6-tridecene, 1-pentadecene, 8-heptadecene, 13-heptacosene, etc.

Another class of hydrocarbons which may be formed into complexes with urea, according to the process of the present invention are the normal diolefins such as 1,2-butadiene, 1,3-butadiene, 1,2-pentadiene, 1,3-pentadiene, 1,4-pentadiene, 1,2-hexadiene, 1,3-hexadiene, 1,4-hexadiene, 1,5-hexadiene, 2,3-hexadiene, 2,4-hexadiene, 1,3-heptadiene, 1,6-heptadiene, 2,4-heptadiene, 1,4-octadiene, 1,5-octadiene, 1,7-octadiene, 2,6-octadiene, 3,5-octadiene, 1,5-nonadiene, 1,8-nonadiene, 2,6-nonadiene, 1,3-deca-

diene, 1,4-decadiene, 1,9-decadiene, 2,8-decadiene, 3,7-decadiene, 2,6-dodecadiene, 1,17-octadecadiene, etc.

Normal hydrocarbons of a greater degree of unsaturation which form crystalline complexes with urea by the process of the present invention include the triolefins, acetylenes, diacetylenes, olefin-acetylenes and the diolefin-acetylenes, including 1,3,5-hexatriene, 1,3,5-heptatriene, 2,8,6-octatriene, ethylacetylene, propylacetylene, butylacetylene, amylacetylene, caprylidene, 4-octyne, diacetylene, propyl-diacetylene, 1,8-nonadiyne, 1-hepten-3-yne, 1,5-hexadien-3-yne, etc.

Normal alcohols, especially those having six or more carbon atoms, may be treated by the present process to form complexes with urea. These include the aliphatic monohydric alcohols such as hexyl alcohol, heptyl alcohol, octyl alcohol, nonyl alcohol, decyl alcohol, dodecyl alcohol, cetyl alcohol, carnaubyl alcohol, and the polyhydric alcohols, such as ethylene glycol, diethylene glycol, propylene glycol and hexitol.

Ethers of normal structure forming complexes with urea include acetal, dioxane, paraldehyde, crotonyl ether, etc. Aldehydes of normal structure also respond to the process of this invention, including butyraldehyde, valeraldehyde, caproaldehyde, palmitic aldehyde, citral, adipaldehyde, etc.

Ketones which form urea complexes are exemplified by 3-hexanone, palmitone, 2,3-pentanedione, etc. Acids also may be treated according to the subject process. Typical normal acids forming urea complexes are the normal fatty acids, especially those having four or more carbon atoms, such as butyric, valeric, caproic, enanthyllic, caprylic, pelargonic, capric, undecylic, lauric, tridecoic, myristic, pentadecanoic, palmitic, margaric, stearic, etc., acid. Acrylic acids also respond, such as methylacrylic acid, tiglic acid, oleic acid, etc. The acetylene acids form urea complexes. These include sorbic and linoleic acids.

Other types of normal-structured compounds which may be treated according to the process of the present invention include esters, such as amyl acetate, ethyl stearate, etc.; amines such as n-decyl amine, dibutyl amine and triethyl amine; amides, such as stearamide; mercaptans, such as heptyl mercaptan; and other organic compounds of normal structure, including halogenated derivatives of the above compounds, thioalcohols, alkyl hydrazines, thioaldehydes, amino acids, nitroparaffins, etc.

The mixtures containing the organic compounds of normal structure may be composed solely of mixed normal compounds, or they may contain materials substantially inert toward urea, such as branched paraffins, isoolefins, aromatics, cycloparaffins, etc. Usually, especially when treating natural products such as petroleum, the inert ingredients are present as isomers of the normal structure compounds, and may occur therewith naturally or by reason of some treatment to which the organic material has been subjected, such as alkylation, cyclization, isomerization, etc. However, active or inert diluents or solvents may be added to normal organic compounds in order to modify the type and degree of crystallization of the latter with urea. The reason for and use of diluents is discussed hereinafter.

Hydrocarbons which form complexes with thiourea are those having a predominating member which is a substantially branched radical or

75

a naphthalene radical, such as alkaryl hydrocarbons wherein at least one alkyl group is an isoparaffin radical of about six or more carbon atoms.

Isoparaffins which form complexes with thiourea include isobutane, isopentane, 2,2-dimethylpropane, isohexane, 2,3-dimethylbutane, 2-methylpentane, 3-methylpentane, 2-ethylbutane, 2-ethylpropane, 1,1-dimethylpentane, 1,2-dimethylpentane, 1,3-dimethylpentane, 1,4-dimethylpentane, 2-ethylpentane, 3-ethylpentane, 2-n-propylbutane, 2-isopropylbutane, 2-methylhexane, 3-methylhexane, 2,2-dimethylpentane, 2,3-dimethylpentane, 2,4-dimethylpentane, 3,3-dimethylpentane, 2,2,3-trimethylbutane, 4-methylheptane, 3-ethylhexane, 2,2-dimethylhexane, 2,3-dimethylhexane, 2,4-dimethylhexane, 2,5-dimethylhexane, 3,3-dimethylhexane, 3,4-dimethylhexane, 2,2,3-trimethylpentane, 2,2,4-trimethylpentane, 2,3,3-trimethylpentane, 2,3,4-trimethylpentane, 2,2,3,3-tetramethylbutane, 2-methyl-3-ethylpentane, 3-methyl-3-ethylpentane, 2-methyloctane, 3-methyloctane, 4-methyloctane, 2,2-dimethylheptane, 2,3-dimethylheptane, 2,4-dimethylheptane, 2,5-dimethylheptane, 2,6-dimethylheptane, 3,3-dimethylheptane, 3,4-dimethylheptane, 3-ethylheptane, 4-ethylheptane, 2,2,3-trimethylhexane, 2,2,4-trimethylhexane, 2,2,5-trimethylhexane, 2,3,3-trimethylhexane, 2,3,4-trimethylhexane, 3,3,4-trimethylhexane, 2-methyl-3-ethylhexane, 2-methyl-4-ethylhexane, 2,2,3,3-tetramethylpentane, 3,3-diethylpentane, 2,2-dimethyl-3-ethylpentane, 2,3-dimethyl-3-ethylpentane, 2,4-dimethyl-3-ethylpentane, 2,5-dimethyl-3-ethylpentane, 2-methyl-4-ethylhexane, 2,2,3,3-tetramethylpentane, 3,3-diethylpentane, 2,2-dimethyl-3-ethylpentane, 2,3-dimethyl-3-ethylpentane, 2,4-dimethyl-3-ethylpentane, 2,2,3,4-tetramethylpentane, 2-methylnonane, 3-methylnonane, 4-methylnonane, 5-methylnonane, 2,2-dimethyloctane, 2,3-dimethyloctane, 2,4-dimethyloctane, 2,5-dimethyloctane, 2,6-dimethyloctane, 2,7-dimethyloctane, 3,3-dimethyloctane, 3,4-dimethyloctane, 3,6-dimethyloctane, 4,5-dimethyloctane, 3-ethyloctane, 2,2,3-trimethylheptane, 2,3,3-trimethylheptane, 2,3,6-trimethylheptane, 2,3,6-trimethylheptane, 2,4,4-trimethylheptane, 2,4,6-trimethylheptane, 3,3,5-trimethylheptane, 3-methyl-3-ethylheptane, 4-propylheptane, 4-isopropylheptane, 2,2,3,3-tetramethylhexane, 2,2,3,4-tetramethylhexane, 2,2,5,5-tetramethylhexane, 2,2-dimethyl-4-ethylhexane, 3,3,4,4-tetramethylhexane, 3,3-diethylhexane, 3,4-diethylhexane, 2,2,4-trimethylheptane, 2,2,4,5-tetramethylhexane, 2-methyl-5-ethylheptane, 4-methyldecane, 5-methyldecane, 2,3-dimethylnonane, 2,4-dimethylnonane, 2,5-dimethylnonane, 2,6-dimethylnonane, 3,3-dimethylnonane, 4-ethylnonane, 5-ethylnonane, 2,3,7-trimethyloctane, 2,4,7-trimethyloctane, 2,2,3,3-tetramethylheptane, 2,2,4-trimethyloctane, 2,2,4,6-tetramethylheptane, 2,2,4,5-tetramethylheptane, 3-methylundecane, 4-methylundecane, 2,3-dimethyldecane, 2,5-dimethyldecane, 2,6-dimethyldecane, 2,9-dimethyldecane, 3-ethyldecane, 5-propylnonane, 2,2,7,7-tetramethyloctane, 2,3,6,7-tetramethyloctane, 2,4,5,7-tetramethyloctane, 3,3,6,6-tetramethyloctane, 2-methyl-5-propylcyclohexane, 3,6-diethyloctane, 2,6-dimethyl-3-isopropylheptane, 4,5-diethyloctane, 2,2,4,6,6-pentamethylheptane, 5-methyldodecane, 2,10-dimethylundecane, 2,5,9-trimethyldecane, 4-propyldecane, 4-ethylundecane, 5-butylnonane, 2,11-dimethylundecane, 4,5-diisopropylcyclohexane, 2,7-dimethyl-4,5-diethylcyclohexane, 4-propylundecane, 2,7-dimethyl-4-isobutylcyclohexane, 2,6,10-trimethylundecane, 2,6,11-trimethylundecane, 6-methyl-7-ethylundecane, 5-propyl-

dodecane, 6-propylundecane, 4-methyl-6-propylundecane, 6,9-dimethyltetradecane, 7,8-dimethyltetradecane, 3-ethyltetradecane, 5,7-diethylundecane, 2,6,7,11-tetramethylundecane, 4,7-dipropylundecane, 2,2,3,3,6,6,7,7-octamethylundecane, 3,12-diethylundecane, 2,6,11-trimethyl-9-isobutyldodecane, 2,6-dimethyloctadecane, 5,7,9-triethylundecane, 2-methyl-4-isobutylhexadecane, 2,9-dimethyl-5,6-diisooamylundecane, 4,8,13,17-tetramethylicosane, 2,11-dimethyl-5,8-diisooamylundecane, 10-nonyl-nonadecane, 2,6,10,14,18,22-hexamethyltricosane, 2,6,12,16-tetramethyl-9-(2,6-dimethyloctyl) heptadecane, etc.

As stated hereinbefore another type of hydrocarbon which readily forms complexes with thiourea is that of the naphthalenes. Typical species of this group include cyclopropane, methylcyclopropane, 1,1-dimethylcyclopropane, 1,2-dimethylpropane, ethylcyclopropane, 1,1,2-trimethylcyclopropane, 1,2,3-trimethylcyclopropane, 1-methyl-2-ethylcyclopropane, propylcyclopropane, 1-methyl-2-propylcyclopropane, cyclobutane, methylcyclobutane, ethylcyclobutane, 1,2-dimethylcyclobutane, propylcyclobutane, isopropylcyclobutane, 1,2-diisopropylcyclobutane, 1,2-dimethyl-3,4-diethylcyclobutane, 1,1,2,2-tetramethyl-3,4-diisopropylcyclobutane, cyclopentane, methylcyclopentane, 1,1-dimethylcyclopentane, 1,2-dimethylcyclopentane, 1,3-dimethylcyclopentane, ethylcyclopentane, propylcyclopentane, isopropylcyclopentane, 1,1,3-trimethylcyclopentane, 1-methyl-2-ethylcyclopentane, 1-methyl-3-ethylcyclopentane, butylcyclopentane, isobutylcyclopentane, 1-methyl-2-propylcyclopentane, 1,3-dimethyl-2-ethylcyclopentane, 1,3-dimethyl-5-ethylcyclopentane, 1,1-diethylcyclopentane, amylcyclopentane, isoamylcyclopentane, 2-cyclopentylpentane, 1-methyl-3-butylcyclopentane, 1-methyl-2,5-diethylcyclopentane, 1,2,3-trimethyl-4-isopropylcyclopentane, heptylcyclopentane, cyclohexane, methylcyclohexane, ethylcyclohexane, 1,1-dimethylcyclohexane, 1,2-dimethylcyclohexane, 1,3-dimethylcyclohexane, 1,2,3-trimethylcyclohexane, 1,3,5-trimethylcyclohexane, butylcyclohexane, 1-methyl-4-ethylcyclohexane, 1-methyl-3-propylcyclohexane, 1,3-dimethyl-5-ethylcyclohexane, 1,3-diethylcyclohexane, amylcyclohexane, pentamethylcyclohexane, 1,2-dimethyl-3,6-diethylcyclohexane, 4-cyclohexylheptane, 3-cyclohexyl-3-ethylpentane, triisopropylcyclohexane, 2,8-dimethyl-5-ethyl-5-cyclohexylnonane, 1-methyl-4-isopropyl-2-dodecyclohexane, octadecyclohexane, propylcycloheptane, etc.

The ratio of the complex-forming agent to active organic compounds will vary with the type of mixture to be treated and with the conditions of complex formation. For example, the extractive fractionation may be carried out with the intention of removing from the mixture the maximum amount possible of the compounds of normal structures present. In this particular case, it is preferred practice to contact the mixture with urea employed in an amount in excess of that necessary for complete complex formation.

Complexes may be formed having varying amounts of the complex-forming agent combined with the active organic compound. When the temperature or other conditions during complex formation are such that about 3 mols of the agent combined with about every 4 carbon atoms of the active organic compound, it is preferred prac-

tice to contact the active organic compound with an amount of the agent somewhat in excess of this ratio.

The formation, separation and purification of the complexes having been accomplished as described hereinbefore, there remains the step of decomposing the complexes in order to recover the active organic compounds present therein. While a number of methods have been found for effecting such a decomposition or regeneration, the following methods have been found to be the most satisfactory for use when carrying out the process of the present invention:

- A. Simple distillation.
- B. Steam distillation.
- C. Application of a solvent for the complex-forming agent.
- D. Heating.

E. Application of a solvent for a particular fraction of the regenerated organic compounds.

The complexes, as has been pointed out hereinbefore, are relatively unstable formations which appear to be loose combinations involving hydrogen bonding or some form of molecular attraction, the exact nature of which has not been deduced. It has been found that due to their unstable character, splitting into the component parts of the complex may be readily accomplished, the complex-forming agent and the organic compounds in complex combination therewith separately recovered in their original state.

By subjecting the complexes to distillation simultaneous destruction of the complex and fractionation of the organic compounds regenerated therefrom may be accomplished. The distillation may take place under normal or reduced pressures and the temperature and pressure are so adjusted that the complexes are readily destroyed and the compounds regenerated therefrom are distilled into fractions which can be utilized for the purposes considered herein. For example, if it is desired to enrich the feed with low boiling normal hydrocarbons, complexes of urea and a mixture of normal hydrocarbons may be decomposed by distillation and the distillant may be recycled to the mixer.

Steam distillation is a refinement of the above process and the principle of regeneration and fractionation applies here as well. Steam distillation is preferable where the organic compounds to be regenerated are of such high boiling point that their distillation would be accomplished by substantial decomposition.

A further type of regeneration comprises addition of a solvent for the complex-forming agent such as water or alcohol to the complex and the application of heat to facilitate the regeneration. By this means the regenerated organic compounds separate from the solution of the complex-forming agent and subsequently may be fractionated by normal purification or fractionation procedures.

A more preferred type of regeneration comprises the addition of a solvent for one or more fractions of the organic compounds to be regenerated from the complexes. When such a mixture is heated the complex decomposes, thus regenerating the organic compounds and complex-forming agents and, in presence of such a solvent, a solution of part of the regenerated organic compounds which form and may be readily separated from the insoluble fractions which are present. Hence, fractionation according to solubility may be readily accomplished.

Fractionation by simple heating is satisfactory

for some purposes. Following the regeneration by such means it is usually necessary to purify or fractionate the regenerated compounds and the regenerated complex-forming agent for further use.

The process of the present invention is useful for the preparation of high octane gasoline or of high Diesel index fuel as well as for the preparation of internal combustion engine fuels having a narrow boiling range.

I claim as my invention:

1. In the process of fractionating a mixture of organic compounds, said mixture containing a fraction A comprising substantially straight-chain materials and a fraction B comprising predominantly non-straight-chain materials, wherein said mixture is treated with urea and the crystalline complexes which form between urea and at least part of fraction A are separated from fraction B, said treatment being conducted below the decomposition temperatures of said complexes, the improvement which comprises recycling at least part of the fraction A thus separated to enrich additional amounts of the original mixture prior to its treatment with urea, forming crystalline complexes by treatment of the enriched mixture with urea and separating said complexes from unreacted material by filtration, said enriched mixture of complexes forming a more porous filter cake.
2. In a process for the fractionation of a mixture of petroleum hydrocarbons, said mixture containing a fraction A comprising substantially straight-chain hydrocarbons, and a fraction B comprising non-straight-chain hydrocarbons, wherein said mixture is treated with urea and the crystalline complexes so formed between fraction A hydrocarbons and urea are separated from fraction B, said treatment being conducted below the decomposition temperatures of said complexes, the improvement which comprises recycling at least part of the complexes of fraction A to enrich additional quantities of the original mixture prior to the urea treatment, forming crystalline complexes by treatment of the enriched mixture with urea and separating said complexes from unreacted material by filtration, said enriched mixture of complexes forming a more porous filter cake.
3. In a process for the fractionation of a mixture of organic compounds, said mixture containing a fraction A comprising branched-chain compounds and a fraction B comprising straight-chain compounds, wherein said mixture is treated with thiourea, and the crystalline complexes so formed between fraction A compounds and thiourea are separated from fraction B, said treatment being conducted below the decomposition temperatures of said complexes, the improvement which comprises recycling at least part of fraction A thus separated to enrich additional amounts of the original mixture prior to treatment with thiourea forming crystalline complexes by treatment of the enriched mixture with thiourea and separating said complexes from unreacted material by filtration, said enriched mixture of complexes forming a more porous filter cake.
4. In a process for the fractionation of a mixture of petroleum hydrocarbons, said mixture containing a fraction A comprising isoparaffins and naphthenes, and a fraction B comprising substantially unbranched hydrocarbons, wherein said mixture is treated with thiourea and the crystalline complexes so formed between thiourea and

fraction A hydrocarbons are separated from fraction B, said treatment being conducted below the decomposition temperatures of said complexes, the improvement which comprises recycling at least part of fraction A thus separated to enrich additional amounts of the original mixture prior to treatment with thiourea forming crystalline complexes by treatment of the enriched mixture with thiourea and separating said complexes from unreacted material by filtration, said enriched mixture of complexes forming a more porous filter cake.

5. In a process for the fractionation of a mixture of organic compounds by treatment with a complex-forming agent of the group consisting of urea and thiourea, said mixture comprising a fraction A containing compounds capable of forming crystalline complexes with the agent and a fraction B containing compounds incapable of a complex formation with said agent, wherein crystalline complexes of the agent and at least a part of fraction A are formed by treating the mixture with the agent below the decomposition temperatures of said complexes, the improvement which comprises recycling at least part of said complexes to enrich additional amounts of the original mixture prior to treatment with the agent, forming crystalline complexes by treatment of the enriched mixture with the complex-forming agent and separating said complexes from unreacted material by filtration, said enriched mixture of complexes forming a more porous filter cake.

6. In a process for the fractionation of a mixture of organic compounds by treatment with a complex-forming agent of the group consisting of urea and thiourea, said mixture comprising a fraction A containing organic compounds capable of forming crystalline complexes with the agent and a fraction B containing organic compounds incapable of complex formation with said agent, wherein crystalline complexes of the agent and at least a part of fraction A are formed by treating the mixture with the agent below the decomposition temperatures of said complexes, the im-

5 provement which comprises recycling at least part of fraction A thus separated to enrich additional amounts of the original mixture prior to treatment with the agent, forming complexes by treatment of the enriched mixture unreacted material by filtration, said enriched mixture of complexes forming a more porous filter cake.

10 7. In a process for the fractionation of a mixture of hydrocarbons by treatment with a complex-forming agent of the group consisting of urea and thiourea, said mixture comprising a fraction A containing hydrocarbons capable of forming crystalline complexes with the agent and a fraction B containing hydrocarbons incapable of complex formation with said agent, wherein crystalline complexes of the agent and at least a part of fraction A are formed by treating the mixture with the agent below the decomposition temperatures of said complexes, the improvement which comprises recycling at least part of fraction A thus separated to enrich additional amounts of the original mixture prior to treatment with the agent, forming complexes by treatment of the enriched mixture unreacted material by filtration, said enriched mixture of complexes forming a more porous filter cake.

LLOYD C. FETTERLY.
